UNITED STATES PATENT OFFICE.

WACLAW POKRZYWA, JOSEF MATYGA, AND STEPHEN LEWANDOWSKI, OF MILWAUKEE,
WISCONSIN.

SAFETY CRANK FOR ENGINES.

Application filed April 25, 1922. Serial No. 556,384.

To all whom it may concern:

Be it known that we, WACLAW POKRZYWA, JOSEF MATYGA, and STEPHEN LEWANDOWSKI, all citizens of the United States, and residents of Milwaukee, in the county of Milwaukee and State of Wisconsin, have invented certain new and useful Improvements in Safety Cranks for Engines; and we do hereby declare that the following is a full, clear, and exact description thereof.

Our invention relates to an improved safety crank, designed especially for cranking engines of the internal combustion type.

The general object of the invention is to provide a structure by means of which the danger of injury due to a premature explosion before the engine crank has passed the dead center is entirely eliminated.

The invention consists further in certain details of construction and combinations thereof which will be more particularly described in connection with the accompanying drawing and subsequently claimed.

In the drawing:

Figure 1 is a longitudinal sectional view of our invention.

Figure 2 is a front elevation thereof, with the cover removed.

Figure 3 is a longitudinal section thereof taken at right angles to the plane of Figure 1.

Referring in detail to the drawing, numeral 5 designates a hollow shank in one end of which is journaled a handle 6, having a reduced portion 7 which is retained by a suitable collar 8 or equivalent fastening device.

The other end of the shank 5 is provided with an enlarged head 9, centrally of which is journaled a spindle 10, having at its outer end a socket 11 for engaging the crank shaft of the engine.

The head 9 is formed with an enlarged internal recess 12 into which projects the squared end 13 of the spindle 10. A cog

wheel 14 is carried by the projecting end 13 and secured thereon by a cotter pin or the like 15, which is retained in position by a spacing block 16, which is countersunk in the head 9, as shown at 17 in Figure 2. These parts are retained within the head 9 by means of a cover plate 18 which is pro-

vided with depending angular lugs 19, which are engaged in bayonet slots 20 formed in the head.

A flexible cord or cable 21 is suitably secured in the reduced portion 7 of the handle by any suitable means, such for example as indicated by the knotted end 22 in Figure 1. The reduced portion 7 is also provided with a circumferential groove 23, within which the cord 21 is laid as the handle 6 is rotated. The other end of the cord 21 is suitably secured to a flat strip of spring steel 24, which is carried around the cog wheel 14, and provided with an enlarged end having teeth 25 adapted to engage with the teeth of the wheel.

In the operation of our invention it will be understood that the operator will grip the handle 6, and in turning the crank the handle will be gradually rotated, thus winding the cord 21 around the reduced end 7 and laying the same in the groove 23. This operation will shorten the effective length of the cord and draw the strip 24 inwardly, causing the teeth 25 to engage the wheel 14 and lock the same to the crank. Thereupon, revolution of the crank will turn the engine. If, however, a premature explosion takes place the wheel 14 will turn backwardly, jerking upon the cord 21, and the head 25 will be thrown backwardly into the corner 26 of the recess 12 and disengage the wheel 14 from the crank and permit the same to revolve freely. The shank 5 is thereby released from the spindle 10 and socket 11 and all danger of injury to the person using the crank is thereby eliminated.

Although we have shown and described specifically one construction by means of which our invention may be carried out, it will be understood that various modifications may be made in the details thereof without departing from the spirit of the invention.

We claim as our invention the following:

The combination with a crank having a hollow shank, of a socket member journaled in one end of the shank, a handle journaled in the other end thereof, a cog wheel keyed to the socket member and housed within the crank, and a flexible member within the

shank, one end of the flexible member being secured to the handle and the other end being positively engageable with the cog wheel upon rotation of the handle in one direction and releaseable therefrom upon rotation of the handle in the other direction.

In testimony that we claim the foregoing

we have hereunto set our hands at Milwaukee, in the county of Milwaukee, and State of Wisconsin.

WACLAW POKRZYWA.

JOSEF MATYGA.

STEPHEN LEWANDOWSKI.
